UNITED STATES PATENT OFFICE.

ISAAC P. OSBORN, OF FLORIDA, INDIANA.

FENCE.

SPECIFICATION forming part of Letters Patent No. 500,032, dated June 20, 1893.

Application filed November 30, 1892. Serial No. 453,584. (No model.)

To all whom it may concern:

Be it known that I, ISAAC P. OSBORN, a citizen of the United States, and a resident of Florida, in the county of Madison and State of Indiana, have invented certain new and useful Improvements in Fences; and I do declare the following to be a full, clear, and exact description of the invention, such as will enable others skilled in the art to which it appertains to make and use the same, reference being had to the accompanying drawings, and to letters of reference marked thereon, which form a part of this specification.

Figure 1 of the drawings is a front view of the fence. Fig. 2 is a rear view showing one of the pickets raised. Fig. 3 is a front view. Fig. 4 is a rear view showing how it may be swung from the center when used as a gate; and Fig. 5 is a perspective view in detail of one of the rails. Fig. 6 is a plan view of one of the rails.

This invention has relation to certain new and useful improvements in fences, and it consists in the novel construction and combination of parts, all as hereinafter described and pointed out in the claims.

In the accompanying drawings, I have illustrated one section of my improved fence, each section being substantially the same.

In the said drawings, the letters A, A, designate the end posts of the section, and B the center post.

C designates the longitudinal rails, which are three in number, and spaced about equally distant from each other, the lower rail being a short distance above the ground, and the upper rail near the upper ends of the posts. Said rails and posts may be made of wood or metal, although metal is preferred on account of durability, the increased expense being somewhat offset by casting them hollow, instead of being solid, as when wood is employed. Said rails are each in the form of a segment of an elongated cylinder, and are placed with their rounded sides uppermost, whereby they offer the least resistance to the wind. They are secured to the end posts by means of tongues b, which enter sockets c, and are held by pins or bolts d. At the center posts, notches are cut in both the post and rail, as shown. The posts should also be bevelled on their faces, as shown at f, in order to present little resistance to the wind.

When the fence is designed to be used as an inclosure for horses or cattle, the wires E, 55 E', are usually employed, the wire E passing along the top of the fence through the upper ends of the posts, and the wire E' passing midway between the middle and upper rails, and also preferably passing through the posts. 60 By making the two wires in one piece, as shown in the drawings, with the connecting end portions g, said wires are also enabled to serve as a truss or brace for the section. Said wires are preferably barbed.

F, F, &c., are the vertical rods or wires which form what may be termed the pickets of the fence, and consist each of a piece of heavy wire, turned at its upper end into a hook h, which holds it in place. Said rods 70 pass through vertical holes or apertures in the lower and middle rails, their lower ends being extended sufficiently to close the space between the lower rail and the ground. The frequency with which the rods are placed 75 will depend upon the particular purpose of the fence, they being much thicker for hogs, sheep, or poultry, than for cattle and horses.

In case it is desired to make an opening in any part of the fence, in order to drive hogs, 80 sheep, or poultry out of or into the inclosure, it is only necessary to raise one or more of these rods, as indicated in the drawings, supporting it in its raised position by engaging its hook h with the wire E', or with the upper 85 rail. In order to give stability and strength to the section, an occasional pair of the rods is extended up and through the upper rail, the upper ends being united by the bow H. In the drawings, I have shown one pair of 90 rods on each side of the center post, as so extended. The rails may be made to swing on the center post, so that by removing the securing bolts or pins, any section of the fence may be easily converted into a gate for temporary or permanent use. In order to accomplish this, the bolts or pins are removed from the section, which is partially removed from the posts and moved endwise sufficiently to allow one end to clear the end post. The section may then be swung around at right angles with the center post; or the rails of any

section may be hinged at one end to the end post, thereby converting the section into a gate, which may be opened by removing the bolts or pins at the center and other end.

5 The advantages of a fence constructed as above described, are as follows: First, it is neat in appearance, strong, effective and durable; second, any section may be taken out for repairs, or be converted into a gate, with

10 very little trouble; third, it affords very little resistance to the wind, and is so constructed as to render it impossible for snow to bank or drift against it to any extent; fourth, the rods or pickets may be quickly 15 raised to form an opening or exit; fifth, the principal weight is upon the middle rail, which supports the rods, instead of upon the lower rail, the extended rods imparting great stability to the section.

20 Having described this invention, what I claim, and desire to secure by Letters Patent, is—

1. A fence section, comprising the end and middle posts, having beveled faces, the semi-25 cylindrical rails placed with their rounded

faces uppermost, the series of short vertically movable rods or pickets passing through the middle and lower rails and having hooked upper ends, and the extended pairs of said rods passing through the upper rail, and 30 united above said rail, said rails being removably secured to said posts, and adapted to swing on the center post, substantially as specified.

2. A fence section, comprising the end posts, 35 the middle post, upper, lower and middle rails removably secured to said posts, the series of vertically movable rods or pickets having the hooks at their upper ends, pairs of said rods or pickets being extended through the upper 40 rail and united, and the wires strung above the upper ends of said series of rods or pickets, substantially as specified.

In testimony whereof I affix my signature in presence of two witnesses.

ISAAC P. OSBORN.
